(57) **CLAIM**

The ornamental design for a terrarium, as shown and described.

DESCRIPTION

FIG. 1 is a top perspective view of the terrarium according to the present invention.

FIG. 2 is a front elevational view of the terrarium of FIG. 1.

FIG. 3 is a back elevational view of the terrarium of FIG. 1.

FIG. 4 is a left side elevational view of the terrarium of FIG. 1.

FIG. 5 is a right side elevational view of the terrarium of FIG. 1.

FIG. 6 is a top plan view of the terrarium of FIG. 1.

FIG. 7 is a bottom plan view of the terrarium of FIG. 1; and, FIG. 8 is a bottom perspective view of the terrarium of FIG. 1.

The dashed lines in the figures are for environmental purposes only, and form no part of the claimed design.

1 Claim, 8 Drawing Sheets
